UNITED STATES PATENT OFFICE.

HUGH McCONAUGHEY, OF CLEVELAND, OHIO, ASSIGNOR OF ONE-HALF TO GEORGE M. BUZZARD, OF CLEVELAND, OHIO.

TIE AND RAIL-CLAMP.

1,132,198.

Specification of Letters Patent. Patented Mar. 16, 1915.

Application filed December 2, 1914. Serial No. 875,066.

To all whom it may concern:

Be it known that I, HUGH McCONAUGHEY, a citizen of the United States, and resident of Cleveland, in the county of Cuyahoga and State of Ohio, have invented certain new and useful Improvements in Ties and Rail-Clamps, of which I hereby declare the following to be a full, clear, and exact description, such as will enable others skilled in the art to which it appertains to make and use the same.

The objects of the invention are to provide a metallic tie for the rails of a railway track and the invention also includes resilient means for clamping the rail securely to the tie in such a manner as to permit of a slight amount of yielding of the rail to lateral strains and pressure, such as occur when a train is rounding a curve, and in this manner to prevent injury to the wheel flanges, and the disagreeable shock occasioned to the passengers by the blow upon the rails.

The invention comprises the combination and arrangement of parts and construction of details, hereinafter described, shown in the accompanying drawings and specifically pointed out in the claims.

In the accompanying drawings Figure 1 is a transverse section of the rail showing the tie and clamping device; Fig. 2 is a transverse section of the tie showing a side elevation of the device; Fig. 3 is a view showing a modification of the wedge.

In these views the tie is shown to be channel shaped and is provided with a vertical body portion A, and top and bottom flange members B and C respectively, extending laterally from the body portion.

D is the rail which is firmly seated upon the tie. Upon each side of the rail is a vertical opening a, a in the upper flange B. Through these openings are inserted the holding or clamping dogs E, E, which are provided with the heads e, e, which overlap the flanges d, d, of the rail on each side. The lower extremities of the clamping dogs are provided with horizontally projecting extremities c', c', which are turned toward each other. The resilient wedge H is inserted between the projecting extremities of the aforesaid clamping dogs and the lower face of the upper flange and extends horizontally through the opening o in the vertical body of the tie. This wedge is peculiarly formed of spring metal and has two leaves

spaced apart to give a limited amount of resiliency thereto, and is secured by passing the reduced extremities h, h, through the opening o, and turning them in reverse directions as shown in Fig. 2 to clench them upon the tie body. This spring is formed by folding a bar of steel and then tempering the body portion to harden the same. 60

In Fig. 3 a modified form of wedge is shown in which the larger end of the wedge is open, and the reduced extremity is secured in the opening o by means of a split pin P.

In use a certain amount of resiliency is obtained by means of the rail resting upon the overhanging flange of the tie. In addition, resiliency against lateral pressure upon the rail is obtained by means of the spring wedge, which permits the rail to yield slightly under pressure sufficiently to relieve the shock of a swiftly moving train, without permitting of the slightest relaxing of the grip of the clamping dogs upon the flange of the rail, since the wedge is driven tightly through between the dogs and tie to insure a constant gripping action of the dogs. As 70 the wedge bears down upon the projecting extremities of the dogs, their heads are brought more forcibly into engagement with said rail flanges, and if any spreading action takes place the dogs will fulcrum upon 75 the walls of the openings in the upper flange at L, thus increasing the pressure proportional to the relative position of the fulcrum points to the extremities of the clamping dogs. 90

Having described the invention what I claim as new and desire to secure by Letters Patent is:

1. In combination with a metal tie having an overhanging flange, of a rail transversely seated thereon, and a resilient securing means for said rail comprising a clamping dog upon each side of said rail, each dog passing through an opening in said flange, and each dog having a shoulder adjacent to its inner extremity, each dog having a head engaging said rail, and a wedge shaped spring intermediate between said shoulders on said dog and the lower surface of said flange upon said metal tie. 95 100 105

2. In combination, a metal tie having a horizontal member and a vertical member, a flanged rail mounted upon said horizontal member, said horizontal member having an opening on each side of said rail, a clamp- 110

ing dog passing through each opening and having a head engaging said flanged rail, said dogs also provided with reversely extending shoulders in their inner ends, and 5 a wedge shaped spring seated on said shoulders, and engaging said horizontal flanged member, and means for holding said wedge shaped spring.

3. In combination, a metal tie having a 10 vertical member and an overhanging horizontal member, a rail seated thereon, a pair of clamping dogs engaging the opposite sides of said rail and passing loosely through said

horizontal member, the lower edges of said clamping dogs provided with shoulders, and a two leafed spring, one leaf engaging said horizontal flange and the other said shoulders in said dogs, said spring passing through said vertical member, and means for securing said spring in place.

In testimony whereof, I hereunto set my hand this 16th day of November, 1914.

HUGH McCONAUGHEY.
